UNITED STATES PATENT OFFICE.

FRANK B. SCHUYLER, OF BERKELEY, CALIFORNIA; ELLA S. SCHUYLER EXECUTRIX
OF SAID FRANK B. SCHUYLER, DECEASED.

WASHING MACHINE.

Application filed November 1, 1926. Serial No. 145,536.

This invention relates to clothes washing machines and particularly to a portable type which is adapted to be attached to an ordinary wash tray.

5 The object of the present invention is to generally improve and simplify the construction and operation of washing machines of the character described; to provide a portable type of power-driven washing machine which 10 may be quickly and readily applied or removed with relation to an ordinary wash tray; to provide a washing machine which is adjustable and reversible to permit adjustment to trays of varying sizes and also right 15 or left hand trays; to provide a washing machine in which the drive shaft is extended the entire length of the trays and serves as a support and a drive both for a washing machine and a wringer and furthermore, permits 20 longitudinal movement of the wringer from one tray to another where two or more trays are placed or formed side by side; to provide a washing machine embodying an impeller and a driving mechanism therefor and independent supports for each whereby the 25 impeller may be removed from the tray and the driving mechanism swung clear of the tray.

One form which the invention may assume is shown by way of illustration in the accompanying drawings, in which:

Figure 1 is a plan view of a standard form of two compartment wash tray showing the washing machine, the wringer and the driving mechanism in position thereon, said view 35 also showing the drive mechanism of the washing machine proper partially in section,

Figure 2 is a cross section on the line II—II of Figure 1, showing one of the drive shaft bearings and the cover therefor,

40 Figure 3 is a cross section taken on the line III—III of Figure 1, showing one of the securing brackets,

Figure 4 is a cross section on the line IV—IV of Figure 1, showing another of the securing brackets and the adjustable base extension,

45 Figure 5 is a cross section taken on the line V—V of Figure 1, showing the driving mechanism in horizontal position and connected with the impeller,

Figure 6 is a similar section showing the arm and driving mechanism in vertical position.

Referring to the drawings in detail and particularly to Figures 1, 5 and 6, A indicates 55 a standard form of wash tray which, in this instance, is divided into two compartments B and C, by means of a central partition D. Extending longitudinally on the wash trays is a base member E and extending at right 60 angles thereto is a base member F. The base members E and F are disposed at right angles with relation to each other and are secured together by means of screws 2 or the like so that the base section F may be removed and reversed as will hereinafter be described.

The base section E is provided with a series of interspaced channel members 3, 4 and 5 which support and carry a drive shaft 6. This shaft forms a support for an arm 7 which 70 carries a driving mechanism whereby an impeller 8 is actuated and the shaft also forms a drive and support for a standard form of wringer generally indicated at 9. The base extension F supports an electric driving 75 motor 10 and a reduction gear housing 11 and a coupling 12 is formed between the reduction gearing and the shaft 6 to transmit power thereto.

The bearing member 3 carries a latch pin 80 13. This pin is spring actuated and its inner end normally enters a perforation in the inner arm 7 and thereby locks the same when it assumes a vertical position, as illustrated in Figure 6, or in a horizontal position as shown in Figure 5. This mechanism, together with the driving mechanism carried thereby is adapted to swing about the shaft 6 and is swung to a vertical position when it is desired to clear the tub or wash tray and to 90 a horizontal position when it is desired to drive or operate the impeller 8. All this will, hereinafter, be described.

The perforations in the side wall of the arm 7 are indicated at 14 and 15. The driving 95 mechanism supported by the arm 7 consists of a rack bar 16 on the upper end of which is formed a journal member 17. The shaft 6 is provided with a crank as indicated at 18 and a connecting rod 19 forms a connection between the bearing member 17 and the crank 18 thereby imparting a reciprocal movement to the rack bar 16, when the shaft 6 is rotating.

Formed on the underside of the arm 7 is 100 a bearing member 19^a and journaled therein

is a shaft 20. On the upper end of the shaft is secured a gear 21. This gear meshes with a rack bar 16 and an oscillating movement is, accordingly, transmitted to the shaft 20. 5 The lower end of the shaft has a coupling member 22 and this coupling member is adapted to connect with a vertical shaft 23 which is secured to the impeller 8. The coupling member 22 is provided with a square 10 shaped recess or socket and the upper end of the shaft 23 is similarly shaped. It is, accordingly, only necessary to drop the coupling 22 over the upper end of the shaft 23 when it is desired to drive or oscillate the 15 impeller.

The impeller proper, indicated at 8, may be of any suitable construction. In this instance, a disc-shaped impeller is shown, which is provided with blades or wings 24 and 25 20 on its upper and lower surfaces. These blades serve the usual function of agitating the water and clothing within the tray or tub when the machine is in operation. One of the features of the present invention is to 25 clear tubs entirely of the washing mechanism, for instance, during the wringing operation or otherwise.

Such clearing of the tubs is quickly accomplished in the present instance, as it is only 30 necessary to grasp the arm 7 and swing it to a vertical or full line position shown in Figure 6 and then to remove the impeller and shaft 23 by merely lifting it vertically out of the tub. This leaves the tubs completely free 35 and clear and they can thus be readily cleaned or dried out or clothing may be readily removed when wringing or transferred from one compartment to another. The impeller proper must be supported when in the tub 40 and the bearing member 30 has, accordingly, been provided.

The bearing is nothing more or less than a rounded ball supported by one or more arms 31 secured to the lower side of the base member E and extending downwardly into the tub. These arms lie flush with the vertical rear side of the tub and are bent at the point 32 to extend along the bottom of the tub. The lower end of the impeller is provided with a 45 socket which may be placed directly over the ball bearing 30 and an ample bearing and guide is thus formed for the impeller from which it may also be readily removed, as previously described, by merely lifting it in a 50 vertical direction. The arms 31 consume so little space that their removal is hardly necessary.

The driving shaft 6 is square in cross section between the bearings 4 and 5 and it thus 55 forms a support and a drive for the wringer generally indicated at 9, that is the wringer may be supported on one end by the shaft and at the opposite end by the edge 33 of the tub. The wringer may thus be moved from one compartment to the other and the cloth-

ing can be wrung and transferred from one compartment to the other or from the innermost tub to a basket or other receptacle, as desired.

The bearing members 4 and 5 supporting the squared portion of the drive shaft is best illustrated in Figure 2. The upper part of the bearing is provided with an extension 34 which forms a support for a cover member 35. This cover member is provided for the purpose of covering the drive shaft 6 and the driving end of the wringer 9, thus preventing clothing or the like from becoming arranged about the shaft. The cover 35 is disposed at a sufficient elevation above the shaft 6 to 70 permit free movement of the wringer from one end of the shaft to the other.

It has already been stated that the base section E and F are secured with relation to each other by means of the screws 2, so as to 75 transmit reversal of the position of the base member F. It should also be noted that the opposite end of the base member F is provided with a slideable extending arm 37 which is best illustrated in Figures 1 and 4. The 80 lower side of the arm 37 is provided with gripping jaws 38 and the bolt passing therethrough permits the jaws to securely clamp the upper end of the tub. This secures the 85 base sections E and insures against movement in one direction with relation to the tub and a similar clamp such as shown in Figure 3 secures the base members against movement in the opposite direction. In other words, two clamps have proven more than 90 sufficient to secure the base sections rigidly in position on the tubs when applied.

The arm 37 is adjustable longitudinally of the base member F and when adjusted is secured by a clamping screw 39. This is an advantage, as it permits adjustment of the base section F to take care of tubs of varying widths.

In actual practice, with the mechanism assembled and applied to a wash tray as shown 100 in Figure 1, it is only necessary to place the impeller in the bottom of the tub and to swing the arm 7 downwardly into driving engagement therewith and then to plug in the motor 10 with a source of electric current supply. With the motor in operation, power is transmitted from the motor shaft through the reduction gear 11 to the shaft 6. This operates the crank 18, the rack bar 16 and the gear 21 and as such transmits oscillating movement through the coupling 22 and shaft 23 to the impeller 8.

A drive is, at the same time, transmitted to the wringer and this may also be operated, if desired, and its position may be changed 110 longitudinally by merely sliding it along the squared portion of the shaft. After the washing operation is completed, the current is switched off and the arm 7 raised to a vertical position, where it is secured by the latch 115

pin 13. The impeller and shaft may also be removed, at this time, and the tubs are thus left clear and unobstructed for further operations, such as, rinsing, wringing, cleaning 5 out the tubs, etc.

Another important feature of the present invention is the reversibility of the entire mechanism. This will perhaps, be appreciated when it is realized that most wash trays

10 of the character here shown are placed in a corner, that is abutting the end wall and it is always desirable to place the driving motor against the end wall so as to leave the opposite ends of the tubs free for rinsing and 15 wringing of the clothes. It is obvious that reversal of the several parts of the mechanism will be required to take care of right and left hand tubs. This is taken care of due to the detachable connection between the base 20 sections E and F, that is the section F may assume a position on either side of the base member E.

The arm 7 with its driving mechanism may be reversed and as such may be swung to 25 either side of the base member E and by removing the cover 35, the wringer may be removed and reversed to extend from either side. The entire mechanism is thus reversible to take care of any situation or position and as 30 such may be applied to tubs or wash trays regardless of their position.

Having thus described my invention, what I claim and desire to secure by Letters Patent is:—

35 1. In a washing machine of the character described, a base member consisting of a longitudinally extending base section, a second section extending at right angles thereto, said section being detachably secured to permit it 40 to assume a right angle position at either side of the first named base section, a drive shaft extending from end to end of the first named section and journalled thereon, a driving motor carried by the second named section and 45 adapted to transmit power to the driving shaft, an arm journalled on the first named section at right angles thereto and adapted to be swung from a vertical to a horizontal position on either side of the first named section, a shaft journalled in the arm and assuming a vertical position when the arm assumes either of its horizontal positions, means whereby an oscillating movement is transmitted to said shaft from the drive shaft in 55 either horizontal position of the arm and an impeller connected to and driven by said shaft.

2. A washing machine comprising a base member adapted to be secured to a wash tray, 60 a drive shaft journalled on the base, an arm pivoted on the base and adapted to assume a horizontal or a vertical position with relation to the base, a shaft journalled in the arm and disposed at right angles thereto so as to 65 assume a vertical position when the

arm is in its horizontal position, means whereby an oscillating movement is transmitted to the shaft from the drive shaft, an auxiliary frame secured to the base and extending downwardly into the wash tray, a bearing member on said frame, an impeller journalled on said bearing, and a shaft on the impeller adapted to be connected with the oscillating shaft on the arm. 70

3. A washing machine comprising a base member adapted to be secured to a wash tray, 75 a drive shaft journalled on the base, an arm pivoted on the base and adapted to assume a horizontal or a vertical position with relation to the base, a shaft journalled in the arm and disposed at right angles thereto so as to 80 assume a vertical position when the arm is in its horizontal position, means whereby an oscillating movement is transmitted to the shaft from the drive shaft, an auxiliary frame secured to the base and extending downwardly into the wash tray, a bearing member on 85 said frame, an impeller journalled on said bearing, a shaft on the impeller, and means whereby a driving connection is formed between the impeller shaft and the oscillating shaft when the arm is swung to a horizontal position. 90

4. A washing machine comprising a base member adapted to be secured to a wash tray, 95 a drive shaft journalled on the base, an arm pivoted on the base and adapted to assume a horizontal or a vertical position with relation to the base, a shaft journalled in the arm and disposed at right angles thereto so as to 100 assume a vertical position when the arm is in its horizontal position, means whereby an oscillating movement is transmitted to the shaft from the drive shaft, an auxiliary frame secured to the base and extending downwardly into the wash tray, a bearing member on said frame, an impeller journalled on said bearing, a shaft on the impeller, said impeller and shaft being vertically removable with relation to the bearing, and a coupling member on the oscillating shaft adapted to engage the upper end of the impeller shaft and form a driving connection therewith when the arm is swung to a horizontal position. 105 110

5. In a washing machine of the character described, a base member consisting of a main section and a secondary section, an electric driving motor, a reduction gear carried by the secondary base section, said secondary base section being secured to the main section so as to assume a right angular position with relation thereto and said securing means being detachable to permit the secondary base section to assume a position at either side of the main base section, a drive shaft extending from end to end of the main base section and journalled thereon, said driving shaft adapted to be connected with the reduction gear and driven there- 115 120 125 130

by in either position of the secondary base section, an arm journalled on the main base at right angles thereto and adapted to be swung to assume a horizontal position on either side of the main base section, a shaft journalled in the arm and assuming a vertical position when the arm assumes either of its

horizontal positions, means whereby an oscillating movement is transmitted to said shaft from the drive shaft in either horizontal positions of the arm, and an impeller connected to and driven by said shaft. 10
